UNITED STATES PATENT OFFICE.

LORI M. PAYNE, OF OMAHA, NEBRASKA.

ABDOMINAL SUPPORTER.

1,110,226.

Specification of Letters Patent. Patented Sept. 8, 1914.

Application filed November 20, 1912. Serial No. 734,305.

To all whom it may concern:

Be it known that I, Lori M. PAYNE, a citizen of the United States, residing at Omaha, in the county of Douglas and State of Nebraska, have invented certain new and useful Improvements in Abdominal Supporters, of which the following is a specification.

This invention relates to an abdominal 10 supporter or surgical bandage, and the object is to provide an improved article that may be used upon the persons of either male or female patients when operated upon for appendicitis or other diseases of similar location, so that the natural bodily form may be preserved or maintained, during and after convalescence. The supporter may also be employed to advantage by females during pregnancy and during convalescence after 20 child-birth.

The supporter consists, briefly, of a compression-bandage or body-portion adapted to circumscribe the person of the wearer above the hips, suitably stayed in the back, 25 and supplied either at the front, back or sides with one or more suitable pockets for holding a pad or cushion or plurality of pads, as may be required; and a supporting portion comprising two endless loops each 30 connected with the body-portion and adapted to encircle one of the legs or hips, a web, strip or insertion of substantially triangular or V-shape being employed at the front and below the body-portion for connecting 35 the upper parts of the loops with said body-portion, said triangular part conforming to the normal shape of the lower part of the abdomen and tending to hold the upper parts of the loops together, said supporting- 40 portion operating to sustain the body-portion and preventing it from "working" or moving upwardly. While I do not limit myself to any particular material, I prefer a knitted fabric, and linen, silk or cotton may 45 be used to advantage.

With the foregoing objects in view and others to be mentioned, the invention consists of the novel construction, formation, combination and arrangement of parts as 50 described herein and claimed, and as illustrated in the accompanying drawing, wherein—

Figure 1 is a front view of the supporter, a part of the person of the wearer also being 55 shown. Fig. 2 is a rear view of the same. Fig. 3 is an enlarged detail relating to Fig.

2, being a view in transverse section to clearly show the use of stays inserted within and longitudinally of the bands at the ends of the compression-bandage or body-portion. Fig. 4 is a detail relating to Fig. 1, being a broken away, plan view to show the formation of a pocket and a pad inserted therein. Fig. 5 is a side view of a pad.

Referring now to the drawing for a more particular description, the abdominal supporter consists, in part, of a bandage 6 of suitable fabric adapted to encircle that part of the body of the wearer immediately above the hips, its ends being provided with transverse bands 7 provided with stays 8 of whalebone or other suitable elastic material, to prevent buckling or wrinkling of the fabric, and by means of the lacing α shown in the drawing, said bandage may be maintained in a taut condition, if desired, upon the person of the wearer.

In order that the bandage 6 may be prevented from moving or slipping upwardly, and that a further support may be provided, the pair of endless loops 9 is employed. These loops are alike in form, and by means of seams α , the inner or upper edge of each loop is connected to the lower edge of the bandage, the width of the loops 55 being such that their outer or lower edges β will preferably terminate immediately below the hips of the wearer as shown in the drawing, said loops being incised at their inner portions to provide edges ϵ extending 60 divergently from the medial line to their junction δ with the lower edge at the front side of the bandage 6, and providing edges ϵ 65 extending substantially divergent from the medial line to their junction γ with bands 7, 75 at the terminals of said bandage.

The supporter as thus far described is adapted to cover substantially all of that part of the body of the wearer at and immediately above and below the hips. It 100 should be of such shape that it will correspond substantially to the form of the wearer, and if manufactured of a soft but firmly woven or knitted material, it may be comfortably worn and will sustain the 105 stresses incident to its use, the extremities γ of the loops, when the article is worn, being disposed between the legs and operating as holder-members to prevent an upward movement of the loops and bandage-portion 110 δ .

While I have shown a limited width or

length for the loops and bandage-portion, I do not wish to limit myself in this respect, and they may have such size and proportion as may be required to substantially 5 correspond to the form of the wearer, as above-mentioned. Edges *c* may be said to be outwardly-divergent with reference to each other, and, connected with these edges and with the lower edge at the front of band- 10 age 6, is an insertion, strip or web 10 of substantially V-shape, to operate as a support for the lower part of the abdomen and also, when worn, to maintain edges *c* parallel with the groins of the person. Both 15 of these functions are important. The connection between member 10 and the edges *c* of members 9 is immediately adjacent to the fold or crease where the abdomen joins each thigh, and parallel therewith, and therefore 20 this part of the support, when worn, more nearly conforms to the shape of the person than it otherwise would.

At 11, best shown in Fig. 4, is indicated a pocket provided for the bandage portion 6, 25 within which a pad 12 may be inserted. While this pocket is shown to be substantially at the medial line and at the front of the supporter, it may of course be arranged to be at either side of said line or at the 30 rear part, if desired, the object being to provide an additional pressure against a certain part of the body in the abdominal region, and I do not wish to limit myself to exactness in the location of the pocket, or 35 to the shape, size or degree of solidity of the pad or cushion.

The effect derived by use of the pad, in surgery, will be the correction of any defect in the form of the body occasioned by 40 the operation, and in other instances it may

be worn by females during pregnancy or after child-birth, and the pocket, therefore, should not be limited to any particular location or part of the bandage-portion 6, but should be provided at such part thereof as 45 may be required.

The abdominal support thus described may be used by men or women, its parts being the same in either instance. When worn by women, the hose supporters *h* may 50 add to its usefulness. The several parts and their uses having been fully explained, a further description relating to operation is not necessary.

What I claim and desire to secure by 55 Letters Patent is—

A supporter comprising a bandage adapted to encircle the body of the wearer, at and above the waist line, means for adjustably connecting the ends of the bandage, a plurality of hip and thigh members secured to the lower edge of the bandage, their front end portions being spaced apart near their upper edges and approaching each other at their lower edges, said lower edges forming a continuous portion for encircling each thigh, and a V-shaped device conformable to the figure, connecting the spaced ends of the hip and thigh portions with each other and connecting diagonally each spaced end 65 with the lower edge or waist line of the bandage below the direct line of strain produced by the means connecting the ends of the bandage.

In testimony whereof I have affixed my 75 signature in presence of two witnesses.

LORI M. PAYNE.
